DRAWER PULL WITH REMOVABLE DECORATIVE INSERT

Alan W. Duncan, Oak Park, Ill.

Application December 9, 1953, Serial No. 27,990

Term of patent 7 years

(Cl. D10—8)

To all whom it may concern:

Be it known that I, Alan W. Duncan, a citizen of the United States, residing at Oak Park, in the county of Cook and State of Illinois, have invented a new, original, and ornamental Design for a Drawer Pull With Removable Decorative Insert, of which the following is a specification, reference being had to the accompanying drawing, forming a part hereof.

Fig. 1 is a front elevational view of a drawer pull with removable decorative insert embodying my new design; and

Fig. 2 is a sectional view taken substantially along the line 2—2 of Fig. 1.

I claim:

The ornamental design for a drawer pull with removable decorative insert, as shown.
